UNITED STATES PATENT OFFICE.

JAMES H. BARLEY, OF SEDALIA, MISSOURI.

HARROW.

SPECIFICATION forming part of Letters Patent No. 387,202, dated August 7, 1888.

Application filed December 12, 1887. Serial No. 257,692. (No model.)

To all whom it may concern:

Be it known that I, JAMES H. BARLEY, a citizen of the United States of America, residing at Sedalia, in the county of Pettis and State 5 of Missouri, have invented certain new and useful Improvements in Harrows, of which the following is a specification.

My invention relates to certain improvements in field drag-harrows; and it consists, 10 first, in the combination of a harrow-tooth having its upper end bent passing horizontally through an opening located in the upper portion of the metal tooth bar or rail forming the upper supports for said tooth, the outer bent 15 end thereof having an integral self-retaining head bent or formed thereon, and the lower support for said tooth detachably connected to the lower portion of said bar or rail, to which the upper end of said tooth is attached and 20 supported in position; second, in a harrow-tooth bar or rail having a series of upper and lower tooth-supports, in combination with the harrow-teeth bent at their upper ends passing horizontally through perforations formed through the side of the upper 25 portion of said bar or rail forming the upper supports for the teeth, and having integral self-retaining heads bent or formed on the outer ends of the upper bent arms thereof, 30 whereby said teeth are held in their respective places, the lower supports for the teeth detachably connected to the lower part of said bar or rail, to which the upper ends of said teeth are attached; third, in the combination 35 of a two-part metal harrow-tooth bar or rail detachably connected each one with the other, having tooth-openings at its upper portion, the upper ends of the harrow-teeth bent passing through said openings, the upper bent 40 ends of said teeth having self-retaining heads formed on their outer ends, the lower supports for the teeth detachably connected with the bottom part of said bar or rail; fourth, in a two-part metal harrow-tooth bar or rail having perforations in its upper portion, the upper ends of 45 the harrow-teeth bent passing through said perforations, the outer bent ends of said teeth having integral tooth-retaining heads formed on them, and an angle or L-shaped detachably 50 connected base having perforations through its lower horizontal projecting portion which

receives and forms the lower support for the teeth; fifth, in a two-part metal harrow-tooth bar or rail having perforations in the side of its upper part, and the harrow-teeth bent at their upper ends passing through said perforations, said teeth having integral self-retaining heads formed on the outer ends of the upper bent arms thereof that project through said bar or rail, and an angle or L-shaped base having its vertical portion detachably connected with that part of said bar or rail which supports the upper ends of the teeth, and the lateral projecting flange of said base, having oblong perforations adapted to receive and form the lower supports for the self-adjusting teeth to stand at different angles. 55

The object of this invention is to furnish harrow-tooth bars or rails having upper and lower tooth-supports detachably connected therewith, and the harrow-teeth, bent at their upper ends, inserted in said supports, having integral heads formed on the outer bent ends thereof, whereby said teeth are held in their respective places without the intervention of nuts, bolts, clamps, keys, pins, rivets, or devices of any kind being applied to the upper ends of said teeth. 70

All the advantages gained by the construction of my improved harrow-tooth and rail above referred to I attain by the mechanism as herein described, and illustrated in the accompanying drawings forming part of this specification. 75

Referring to the drawings, Figures 1, 2, 3, 80 and 4 are side elevations of my improved harrow-tooth bar or rail having the usual number of teeth attached in their respective places and supported at different angles. Figs. 5, 6, 7, 8, 10, and 13 are views of tooth-rail in vertical 85 cross-section with teeth attached, showing slight variations in the manner of arranging the upper and lower supports for said teeth. Fig. 11 is a tooth-supporting clamp. Figs. 9 and 12 are top edge views of sections of tooth 90 bar or rail, showing the lower tooth-supports further varied in form. Fig. 14 is a side view of a section of tooth-rail, showing the opening forming the upper tooth-supports varied in form of construction. Figs. 15, 16, and 17 are 95 views of the harrow-teeth in side elevation, showing the upper end bent and having an in- 100

tegral self-retaining head formed on the outer bent end thereof, which is slightly varied in the manner in which said head is formed.

In the drawings, A represents the tooth bar or rail of which the harrow sections are formed, and B are the teeth.

In the embodiment of this invention I employ metal bars, which form the tooth rails A proper. Through the side of the upper portion of said bar a series of openings or perforations, A⁴, are formed, at suitable distances apart, which receive and support the upper ends of the teeth. The lower tooth supports may be formed by the use of an angle or L shaped metal base having its vertical flange A² detachably connected with the lower part of the bar A by bolts or rivets, or any other suitable means may be employed to hold the two parts together. Through the lower laterally-projecting flange, A', forming said base, a series of perforations, A³, relative in number to the perforations A⁴ in the side, are formed, which receive and support the lower portion of said teeth. The upper ends of the teeth are then bent or formed at or near a right angle, forming the horizontal portion B'. The outer end of said bent portion is then either bent pointing downward, upward, or sidewise, or an oval or button shaped head, B², is formed integral therewith, as shown in the drawings, Figs. 15, 16, and 17. The teeth are then inserted through the perforations A⁴ with their lower point ends turned downward to stand as shown in the drawings, Fig. 6. The points of the teeth are then inserted through the perforations A³ in the base-flange A', which is passed up over the teeth, and the flange A² of said angle or L shaped base is attached to the lower portion of the bar A, thus forming the tooth bar or rail complete, as shown in the drawings, Figs. 1, 2, 5, and 7.

When harrows are wanted having the teeth attached rigidly to the rails, the perforations A³ in the base-flange A' are made the size of the teeth to be used, as shown in the drawings, Fig. 2; and when self-adjusting teeth are preferred the perforations A³ in the base-flange are made oblong, as shown in the drawings, Fig. 1, allowing the teeth having a free horizontal movement on their upper bent pivot-arms, B'. The shoulders C C, at alternate ends of said perforations, support the teeth in a vertical position when the harrow is drawn in one direction and in an inclined position when the motion of the harrow is reversed to the opposite direction, as shown in the solid and dotted line drawings, Fig. 1.

The oblong perforations A³, above referred to, may be formed parallel with the rail or base flange A'; or they may be formed either angular or flaring rearwardly, for the purpose of permitting the lower ends of the teeth falling out into a line of travel when working in a slanting position.

I do not restrict myself to using my improved harrow-tooth exclusively in connection with a

bar or rail having an angle or L shaped detachably-connected base, provided with perforations A³, for supporting the lower portions of the teeth, as eye or loop shaped bolts or other suitable metal fastenings may be detachably connected to the bottom portion of said tooth-bars, forming the respective lower supports for each tooth, as shown in the drawings, Figs. 3, 4, 8, 9, 10, 11, 12, and 14. In this instance the teeth may be supported on the rails rigidly by forming the openings in their lower supports the size of the teeth used, as shown in the drawings, Figs. 4, 10, 12, and 14, or said openings may be formed oblong with the rails, allowing the teeth having a horizontal movement on their pivots B' to stand at different angles, as shown in the drawings, Figs. 3, 8, and 9. It is therefore obvious that the special manner of constructing these lower tooth-supports may be further varied in form.

In the drawings, Figs. 4, 10, and 11, an eye or loop shaped screw-bolt, D, is employed having one or more tangs, D', passing through perforations in the lower portion of said rail. These loop-supports may be so formed with sufficient longitudinal space between their two arms or tangs D', adapted to support the teeth either in a vertical or inclined position, as shown in the drawings, Figs. 3, 8, and 9, before referred to. One end of the tooth-supporting arm or tang D' may be bent, forming a hook-shaped end, D², passing through the rail A, while the other arm thereof may pass through said rail, having a thread and nut on its point end D³; or said last-mentioned arm or tang may be formed into an eye, D⁴, to admit of a bolt or rivet, D⁵, passing through said eye and rail, as shown in the drawings, Fig. 9; or, in lieu of said loop, having tangs D' D', as shown and described, the lower tooth-supports may be made of malleable or wrought metal in sections for each tooth, formed in a right angle or L shape, D⁶, having openings through their lower horizontal portion, A', to receive and support the lower ends of said teeth, the vertical part A² thereof being detachably connected to the lower portion of said bar or rail A by bolts or rivets, as shown in the drawings, Figs. 9, 10, and 12, and also at end teeth of rails in the drawings, Figs. 3 and 4.

Either one or both of the upper and lower tooth-supports may be detachably connected to the vertical portion of said tooth bar or rail, as shown in the drawings, Figs. 13 and 14, where a bar or strip of metal, A⁵, may be used, having perforations therein for the upper end of the teeth to enter, or corresponding notches may be formed or rounded out in the top edge of the bar A, and in the lower edge of the bar A⁵, so as to form openings A⁴ the size of the teeth when the two parts are connected in place, each one with the other, by bolts or rivets, as shown at drawings, Fig. 13.

Referring again to my improved tooth having integral self-retaining heads B² formed in the manner shown, either one is equally well

adapted to be used in connection with either of the bars or rails, as shown in the drawings, Figs. 1, 2, 3, 4, and 14.

I am aware that prior to my invention metal harrow-tooth-supporting beams have been used having a lateral projecting flange formed integral with its vertical portion, forming said beam of a single piece of an angle or L shape metal.

10 Having fully described my invention, what I claim as new and useful, and desire to secure by Letters Patent, is—

1. In a harrow, the combination, with metal tooth bars or rails forming the sections thereof having tooth-supports detachably connected with their lower portions, and perforations through the side of their upper portion which receive and support the upper ends of said teeth, of the harrow-teeth having their upper 15 bent ends passing through said perforations, said teeth having integral self-retaining heads formed on the outer ends of their upper bent portion that projects through said bars or rails, whereby said teeth are held in their respective 20 places, substantially as specified.

2. The combination of a metal harrow-tooth bar or rail having holes through the side of its upper portion and the harrow-teeth bent at their upper ends passing through said holes, 25 said teeth having integral self-retaining heads formed on the outer end of their upper bent portion that project laterally through said bar or rail, and the lower supports for said teeth detachably connected with the lower portion 30 of said bar or rail, to which the upper ends of said teeth are attached and supported at different angles, substantially as specified.

3. The combination, with a metal harrow-tooth bar or rail having perforations through 40 the side of its upper portion and the harrow-teeth bent at their upper ends passing through said perforations, said teeth having self-retaining heads formed on the outer end of their upper bent portion that project laterally 45 through said bar or rail, of an angle or L shaped detachably-connected base having perforations through its lower lateral projecting portion which receive and form the lower supports for said teeth, substantially as specified.

50 4. The combination, with a metal harrow-tooth bar or rail having perforations through the side of its upper portion and the harrow-teeth bent at their upper ends passing through said perforations, said teeth having self-retaining heads formed on the outer ends of the 55 upper bent portion thereof, of an angle or L shaped base having its vertical flange detachably connected to the lower portion of said bar or rail that supports the upper ends of said

teeth, and the lateral projecting flange of said 60 L-shaped base, having oblong perforations adapted to support and limit the horizontal movement of the self-adjusting teeth to stand at different angles, substantially as specified.

5. The combination of a two-part metal harrow-tooth-supporting bar or rail detachably connected, each one with the other, having perforations A⁴ in the side of its upper vertical part, A, forming supports for the upper ends of the harrow-teeth, and having corresponding 70 perforations through the lower lateral projecting part, A', of an angle or L shaped detachably-connected base forming the lower supports for said teeth, substantially as specified.

6. The combination of a two-part metal harrow-tooth-supporting bar or rail detachably connected, each one with the other, having perforations A⁴ in the side of its upper part, A, and oblong perforations A³ in the lower lateral projecting part, A', of an angle or L shaped 80 detachably-connected base, substantially as shown and described, and for the purpose specified.

7. The combination of a harrow-tooth and rail, said tooth having its upper end bent, with 85 said bent end passing through a perforation formed through the side of the upper portion of said rail, said tooth having an integral self-retaining head, B², formed on the outer end of the upper bent portion, B', thereof, said head 90 adapted to catch or bear against the opposite side surface of said rail, to which the tooth is applied, and detachably supported at its lower portion, substantially as specified.

8. The combination of a harrow-tooth and rail, the lower tooth-supports detachably connected to said rail, the perforations in the side thereof, and the tooth having a hook-shaped self-retaining head formed on its upper end passing through said perforations, substantially 100 as specified.

9. The combination of the harrow-teeth and rail, the perforations in the side thereof, and the harrow-teeth bent at their upper ends forming hook-shaped self-retaining heads pivotally supported in said perforations, the lower tooth-supports detachably connected with said rail, having longitudinal space between their shoulders adapted to support the teeth either vertically or inclined with respect to the direction in which the harrow is drawn, substantially 105 as specified.

In testimony whereof I affix my signature in presence of two witnesses.

JAMES H. BARLEY.
